US0D1086068S

(12) **United States Design Patent** (10) **Patent No.:** **US D1,086,068 S**
(45) **Date of Patent:** **** Jul. 29, 2025**

(54) **CHARGING ADAPTER**

- (71) Applicant: **Dongguan LanXin Charging Technology Co., Ltd.**, Dongguan (CN)
(72) Inventor: **Jinhua Huang**, Jiujiang (CN)
(73) Assignee: **Dongguan LanXin Charging Technology Co., Ltd.**, Dongguan (CN)

(**) Term: **15 Years**

(21) Appl. No.: **29/894,192**
(22) Filed: **Jun. 7, 2023**
(51) LOC (15) Cl. **13-03**
(52) U.S. Cl. **USPC D13/146**

(58) **Field of Classification Search**

CLAIM

The ornamental design for a charging adapter, as shown and described.

DESCRIPTION

FIG. 1 is a rear, left and bottom perspective view of a charging adapter, showing my new design;

FIG. 2 is a front, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the charging adapter that form no part of the claimed design.

1 Claim, 8 Drawing Sheets
